United States Patent Office.

ALEXANDER HUMPHRIES, OF BETHEL, OHIO.

Letters Patent No. 86,402, dated February 2, 1869; antedated January 20, 1869.

IMPROVEMENT IN SPOKING-MACHINE.

The Schedule referred to in these Letters Patent and making part of the same.

To whom it may concern:

Be it known that I, ALEXANDER HUMPHRIES, of Bethel, Clermont county, Ohio, have invented a new and useful Spoking-Machine; and I hereby declare the following to be a full, clear, and exact description thereof, reference being had to the accompanying drawings, making part of this specification.

The present invention relates to certain improvements on the spoking-machine, patented by myself and John Keethler, on the 30th of July, 1867.

My said improvements consist, first, in providing one of the supporting-standards with adjustment to and from the other, for the purpose of adapting the machine to hubs of different lengths; secondly, in hinging the adjustable frame, by which the set of the spokes is gauged, upon the front of the machine, and supporting it by open notches or crotches at the rear, by which means the work of driving the spokes into the hub, and bringing them to a uniform dish or set therewith, can be both better and more expeditiously performed than was possible with said machine.

Figure 1 is a vertical section of my improved machine, in the plane of the hub's axis.

Figure 2 is a top view of the same.

Figure 3 is a perspective view of the rear portion of the front side of the machine, omitting the lower portion.

Figure 4 is a perspective view of one of the pillow-blocks.

A A' are two sills supporting one fixed standard, B, and one adjustable standard, C, the latter being secured to said sills, by means of nuts D D' and screws E E', which screws occupy slots e e', in the feet of the standard C, said feet being of sufficient length to give the standard a firm bearing upon the sills.

Each standard has near its lower end a rail, F, traversed by a screw, G, for the vertical adjustment of a pillow-block, H, whose upper edge has a notch, h, with converging sides, so as to receive, hold, and centre a hub of any diameter.

The pillow-blocks H are restricted to a vertical adjustment by grooves e'.

Framed permanently into the standards B and C, somewhat higher than and just outside of the pillow-blocks, are two rails, I I', which are traversed by a bolt, J, having a crank, j, at one end, and being screw-threaded, j', to enter a nut, i, on the rail I'.

A hub, Z, (already bored, turned, and mortised,) being laid in the pillow-blocks H, is secured therein by inserting and turning the screw J, until the ends of the hub are held fast by the rails I I', and is clamped firmly down by the two spring-bars L, whose free ends are engaged in racks M.

My rest or gauge N, instead of being hinged over the but-end of the hub, or at the rear of the frame, so as to oblige a double manipulation to clear it from the spoke, as in the patent alluded to, is hinged at the front side of the frame upon a bolt, O, which bolt is screw-threaded at one end, and provided with a nut, o, whereby the two posts of the standards C can be pressed toward each other, in order to impart sufficient friction to the hinge to enable the gauge to be self-sustaining at any position in which it may be placed, when open or lifted from the spoke.

The free end of the gauge has crotches P, which straddle a bolt, O', whose office it is to support the gauge at its lowest or effective position.

These crotches serve to guide the gauge to its place upon the bolt O', and to hold it firmly on said bolt, while permitting the easy elevation of the gauge when desired.

The standards B C are perforated, to allow the bolts O O' to be placed higher or lower in the said standards, to suit the length of spoke, and the gauge-frame has a series of perforations, k, to enable the adaptation of the machine to a hub of any length.

The gauge N has a sliding rest, Q, which is set toward or from the spoke, by means of a cranked or other screw, R, so as to give any desired uniform "dish" to the spokes.

In order to correct a "contrary" spoke, (one disposed to lean away from the true dish,) I have provided a lever, S, pivoted to the frame at S', and whose free end can be caught in a ratchet, T, on the standard.

Attached to this lever, at or about its mid-length, is a chain, U, that terminates in a hook, u, adapted to be engaged round the rear side of the spoke, so as to enable the operator to draw the spoke firmly against the rest aforesaid.

I claim herein as new, and of my invention—

1. In a spoking-machine, the combination of the sills A A', stationary and movable standards B C, and hub-clamping devices J L M, substantially as described, for the purpose specified.

2. The adjustable gauge N Q R, provided with crotches P, resting upon the pin O', in combination with the spoke-setting devices S T U, substantially as and for the purposes set forth.

In testimony of which invention, I hereunto set my hand.

ALEXANDER HUMPHRIES.
